UNITED STATES PATENT OFFICE.

CLAUD DANIEL MCPHEE, OF ARNPRIOR, CANADA.

SIGNALING SYSTEM FOR RAILWAYS AND THE LIKE.

No. 799,752.

Specification of Letters Patent.

Patented Sept. 19, 1905.

Application filed May 5, 1905. Serial No. 258,961.

To all whom it may concern:

Be it known that I, CLAUD DANIEL MCPHEE, electrician, of the town of Arnprior, in the county of Renfrew, Province of Ontario, Canada, have invented certain new and useful Improvements in Signaling Systems for Railways and the Like, of which the following is a specification.

My invention relates to improvements in signaling systems for railways and the like; and the objects of my invention are to provide an electric block-signaling system whereby a train will be automatically stopped if there is another train in the next adjacent section, further objects being to provide means to stop the train if the battery operating the electric signaling system fails to operate and to render the construction of the system as simple and efficient as possible; and it consists, essentially, of a plurality of electrically-insulated track-sections, an open electric circuit in each section designed to be closed by the wheels and axles of the train in that section, means whereby the closure of the said circuit in two succeeding sections closes a third electric circuit, and means whereby the closure of the third electric circuit stops the train at the end of the section, the various parts of the device being constructed and arranged in detail, as hereinafter more particularly described.

Figure 1 shows a diagrammatic view of my system as ordinarily applied in the blocks of track between stations. Fig. 2 shows a diagrammatic view of the arrangements used at the station where a switch is used. Fig. 3 is an enlarged diagrammatic view of the armature and magnet connections shown in Figs. 1 and 2. Fig. 4 shows an enlarged perspective detail of the armature 41 in Fig. 2. Fig. 5 is an elevation of a spring-actuated motor situated in the moving train, the purpose of which is hereinafter to be described. Fig. 6 is a side elevation of the same. Fig. 7 is a sectional view showing a detail of the connections of the compressed-air brake-pipe with the spring-motor.

Referring to Fig. 1, 2, 3, and 4 represent a plurality of blocks of insulated track-section. At the end of each of these blocks two insulated rails 5 and 6 are provided, as shown, the end insulation 7 of each rail being in alignment. Electrical contact is afforded by a

conductor 31 around the rail 6, as shown. *a* and *b* represent two wheels and axles on different parts of a moving train *c*, which are insulated from each other. *d* represents an electric dynamo suitably geared to the wheels of the train, and *e* a spring-actuated motor connected to the air-pipe, as hereinafter described. The circuit is completed through the tracks between the wheels and axles *a* and *b*.

Referring now to Figs. 4, 5, and 6, which show details of the spring-motor *e*, it will be seen that it consists, essentially, of a gear-wheel *f*, provided with a shaft integral therewith which is suitably journaled in the outside casing *g* of the motor. *h* is a strong spiral spring, one end thereof being secured to the frame and the other to the shaft, thus tending to rotate the wheel *f* in the direction indicated by the arrow. The wheel is connected by an idler *i* or other suitable gearing to a similar wheel *j*, to which is secured an annular disk *k*, provided on the periphery thereof with a projecting tooth *l*. *m* is an armature-lever constructed of magnetic material pivoted in the frame at *n*. A counterweight *o* is placed at one end of the lever, tending normally to throw it up. A projecting lug *p* is provided on the end of the lever, adapted to engage the projecting tooth *l* on the disk *k*. *q* is a lever pivotally secured to the frame at the point *r* and adapted to swing in the direction transverse to that of the armature-lever *m* and adapted to engage the top of this lever. A spring *s*, secured to the frame, normally tends to force the lever *q* upwardly. *t* is an electromagnet suitably placed below the lever *m* and designed when energized to draw and hold the lever *m* down, so that the projection *p* on the end thereof will engage the tooth *l* on the disk *k*. A projecting lug *u* is secured to the casing *g* and adapted to engage the end of the lever *m*, thus limiting its upward movement. It will thus be seen that the lever *m* will normally remain at its extreme upward position with the lug *p* out of engagement with the tooth *l* on the disk *k* and having the lever *q* resting on top of it. The spring-motor is so situated relative to the throttle-lever *v* of the locomotive that the said lever in its motion closing the throttle will engage the lever *q*, forcing it down, which forces the lever *f* down, causing the

projection *p* to engage the tooth *l* on the disk *k*. The electromagnet *t* depends for its energy on the dynamo *d*, which is suitably geared to the wheels of the train. It will 5 thus be seen that when the train stops the electric energy will cease, and so the electromagnet becoming deenergized would allow the armature *m* to move upwardly, thus allowing the wheel *f* to rotate; but in shutting 10 off the steam the throttle-lever has been brought across and has forced the lever *g* down, which will continue to hold the armature *m* in its original position, with the projection *p* engaging the tooth *l*. The wheel *f* 15 in the spring-motor is suitably connected to a cylindrical plug *w*, which fits inside a similar cylinder *x*, provided with an opening *y* at one side thereof, to which a compressed-air pipe *z* for operating the air-brakes is connected. 20 A plurality of openings *8* are symmetrically placed around the circumference of the plug *w*, uniting in a central open space *9*, and a single opening *10* is provided in the cylinder *x*. The gearing of the spring-motor is 25 so arranged that every second turn of the disk *k* will bring one of the openings in the plug *w* opposite a similar opening in the cylinder *x*. It will thus be seen that when the openings in the two cylinders are opposite 30 each other the air-brake pipe is open to the air, which will operate the air-brakes. The manner of this operation is quite well known to those familiar with this art and need not be here described. Under normal conditions 35 the spring-motor is set with the air-pipe opening closed; but in the motion of the train should an insulated part of the track intervene between the two wheels and axles *a* and *b* the circuit *c* would be broken, which would 40 deenergize the magnet *t*, which would free the armature *m*, allowing the disk *k* to rotate, which would rotate the plug *w*, opening the air brake-pipes to the air, and so operating the brakes. As the train will pass the 45 insulated section very quickly, the disk *k* will only have time to rotate once, which will leave the air-pipe still open, which will bring the train immediately to a standstill.

Referring now to Fig. 1, which shows the 50 form of electric circuit used in my improved block-signaling system, 11 is an electric circuit consisting of the central battery 12, one side of which is connected directly to one of the rails 13 and the other through an electromagnet 14 to the other side of the rail 15. The rails 13 and 15 are insulated from each other, and it will be seen that when the train comes on the tracks the circuit will be completed through the wheels and axles of the 55 train energizing the magnet 14. 16 is an electric circuit consisting of the same central battery 12, one side of which is connected directly to one side of the tracks in the insulated section 3, and the other side is connected, through the electromagnet 17, to the

other side of the tracks in said section. It will thus be seen that this circuit will be completed as soon as a train comes on to section three and the electromagnet will then be energized. 18 is an electric circuit comprising the same central battery 12, an electromagnet 19, and keys 20 21. This circuit is indicated in dotted lines in the drawings. The keys 20 and 21 are operated by armatures 22 and 23, as hereinafter described. 25 is an armature adapted normally to rest in contact with the button 26, the said armature being situated directly below the magnet 19, whereby when the latter is energized the armature will be raised out of contact with the button 26. The button 26 is connected directly to the dead-rail 5, and the other side of the armature is connected by a conductor 27, (indicated in heavy dotted lines,) through the armature 22 or 23 and buttons 28 or 29 and 80 conductor 30, to the upper rail of the track-section 3. By this means when the armature 25 is in contact with the button 26 electrical connection is afforded between the dead-rail and the rest of the section. It is to be noted 85 that the dead-rail 5 will be electrically connected to the remainder of the track-section if either the armature 22 or 23 is raised into contact with the buttons 28 and 29. Assuming for the sake of illustration that there is 90 a train in each of the blocks 2 and 3, thus completing both the circuits 11 and 16 and energizing the electromagnets 14 and 17, the armatures 22 and 23 will then be raised in 95 contact with the buttons 28 and 29, and so the dead-rail 5 will be put in electrical contact with the rest of the section 3. As, however, the keys 20 and 21 are operated by the armatures 22 and 23, when these are raised both 100 the keys will be closed, so completing the 105 circuit 18, which will energize the magnet 19, which will raise the armature 25 out of contact with the button 26, thus again electrically disconnecting the rail from the rest 110 of the section, and this rail will break the 115 circuit when in a train and stop it, as hereinbefore described. It will be seen that if the rail 5 is electrically disconnected from the 120 rest of the section a train going either way will be stopped as soon as the rails and axles 115 *a* have passed the blocks of insulation 7. Each signaling-station in the system is exactly similar to that hereinbefore described. It is to be noted that should the battery fail to operate the train will be stopped, as under 125 normal conditions, the armatures 22 and 23 being out of contact with the buttons 28 and 29, the rail 5 is electrically disconnected from the remainder of the section, and if only one of these armatures is raised in contact with the button it will again be placed in electrical contact with the section. In this manner 130 it is always insured that the battery is in running order. In the drawings 32 shows a station in which there is a train on one side

of it but not on the other. In this case the circuit 11 has been completed, raising the armature 23 into contact with the button 29, and so placing the rail 5 in contact with the remainder of the section. In '33 a station is shown having no train on either side of it.

Referring to Fig. 2, which shows a more protective form of my device adapted to be used in connection with the central station, where there is a switch, 34 and 35 indicate two signaling-stations provided with circuits exactly similar, as hereinbefore described with reference to Fig. 1. 46 and 48 are the two outside insulated blocks of track, and 47 is the central-station block. 49 is a switch situated in the central block 47, the switching mechanisms 50 and 51 of which are so arranged that when the switch is thrown in at either end a connection will be formed between the two sides of the rail, this being equivalent as far as regards the operation of the signaling system to a train placed in the block. Insulated tracks are provided at each end of the second section, as hereinbefore described for Fig. 1, and two signaling-stations are provided at each end thereof the electrical connections in which are exactly similar to that in Fig. 1 and need not be here again described. An additional circuit 36, however, is added, comprising a battery 37, one pole of which is led through an electromagnet 38, a contact-button 40, an armature 41, a contact-button 43, to one side of the track. The other side of the battery is led through an electromagnet 39, a contact-button 28, an armature 22, to the same side of the track. The armatures 22 and 41 are situated directly below the electromagnets 14 and 17, the armatures normally remaining out of contact with the respective contact buttons.

Referring to Fig. 4, which shows a detail of the connection of the armature 41, it will here be seen that the two armatures 41 and 23 while working on one shaft are still insulated from each other, whereby the circuits 36 and 18 may be kept separate. Directly below the magnets 38 and 39 armatures 44 are situated, coacting with the contact-buttons 45. The contact-buttons are connected to one side of the track and the armature to the other, whereby when the armature comes in contact with the button electrical connection will be afforded between the two tracks. Assuming that we have two trains in the outside section, the circuits 11 and 16 of the signaling-stations 34 and 35, respectively, will be completed, which will energize the electromagnets 14 and 17, which will raise the armatures 22, 23, and 41, which will complete the circuit 36, energizing the electromagnets 38 and 39, which will raise the armatures 44 into contact with the buttons 45. This, however, forming connection between the rails of the central section will complete the circuits 16 and 11 of the signal-stations 34 and 35, respectively, ener-

gizing the electromagnets 17 and 14, raising the armatures 22 and 23, which, as hereinbefore described with regard to Fig. 1, will complete the third circuit 18, operating the electromagnets 19, raising the armature 25, and so leaving a dead-rail at each side of the central section. Thus each train would be stopped at the extremity of the central section. Thus all possibility of the trains even approaching near each other is done away with, as the central block of track always is interposed between them. Assuming for further illustration that a train is in the section 46 and no train in any of the other sections, but that the switch 49 is open, this will act exactly as a train in the central section, which will complete the circuit 16. The outside train in the section 46 will have completed the circuit 11. We will thus have the two circuits 11 and 16 complete, and, as hereinafter described, this will operate the third circuit, which will electrically disconnect the rail 5 from the rest of the section, which will stop the train at that point. It will thus be seen that the only condition in which the train can pass clearly through the section is that there is not a train in the next section past the central section, that the switch 49 is closed, and that the batteries in both the signaling-stations 34 and 35 are in working order.

One of the chief advantages of my system is that it works on an open circuit—that is, the battery is only connected momentarily—and if the battery fails to operate the train is stopped, so that absolute security is thus afforded. It will also be noticed that in my system the stopping of the train does not depend on the train operator taking notice of any signals or the like, as the train is automatically stopped without his aid whether he notes the signals or not. It will be readily understood that electric semaphores might be placed in each of the signal-stations, if desired.

The apparatus used in the construction of my system is all of the very simplest nature and may readily be applied to any line of railway now in use with very little expense.

It will be understood that I do not wish to confine myself to the exact details of construction herein shown and described, as it will be evident that many changes may be made in the form of the electric circuits without materially departing from the spirit of my invention.

What I claim as my invention is—

1. In a block-signaling system in combination a plurality of electrically-insulated track-sections, an open electric circuit in one section adapted to be closed by the wheels and axles of a train in that section, a second electric circuit in the next adjacent section adapted to be closed by the wheels and axles of a train in that section, a third electrical circuit, means whereby the closing of the two circuits in the adjacent sections closes the third circuit.

cuit, and train-stopping means operated by the closure of the third circuit as and for the purpose specified.

2. In a block-signaling system in combination a plurality of electrically-insulated track-sections, an open electric circuit in one section adapted to be closed by the wheels and axles of a train in that section, a second electric circuit in the next adjacent section adapted to be closed by the wheels and axles of a train in that section, a third electrical circuit, means whereby the closing of the two circuits in the adjacent sections closes the said third circuit, means whereby the closing of the said third circuit interposes an electrically-insulated rail between the sections, an auxiliary circuit between two insulated parts of the moving train completed through the tracks between them and means whereby the breaking of said circuit operates the air-brakes as and for the purpose specified.

3. In a block-signaling system in combination a plurality of electrically-insulated track-sections, an open electric circuit in one section adapted to be closed by the wheels and axles of a train in that section, a second electric circuit in the next adjacent section, adapted to be closed by the wheels and axles of a train in that section, a third electrical circuit, means whereby the closing of the two circuits in the adjacent sections closes the third circuit, means whereby the closing of the third circuit interposes an electrically-insulated rail between the sections, an auxiliary circuit between two insulated parts of the moving train completed through the tracks between them, a dynamo, an armature and motor whereby the air-brakes are operated when the said circuit is broken as and for the purpose specified.

4. In a block-signaling system in combination a plurality of electrically-insulated track-sections, an open electric circuit in one section adapted to be closed by the wheels and axles of a train in that section, a second electric circuit in the next adjacent section adapted to be closed by the wheels and axles of a train in that section, a third electric circuit, means whereby the closing of the circuits in the two adjacent sections closes the said third circuit and means whereby the closing of the said third circuit electrically insulates a rail between the two sections as and for the purpose specified.

5. In a signaling system in combination a plurality of electrically-insulated track-sections, an electric circuit in one section adapted to be closed by the wheels and axles of a train in that section, an electromagnet in said circuit, a second electric circuit in the next adjacent section adapted to be closed by the wheels and axles of a train in that section, an electromagnet in said circuit, a third electric circuit, armatures in said circuit adapted to be operated by the magnets in the first two

circuits, contacting points coacting with said armatures whereby when said electromagnets are energized the third circuit will be completed, an electromagnet in said third circuit, an armature adapted to be lifted by said magnet whereby a rail is electrically disconnected from the remainder of the section as and for the purpose specified.

6. In a signaling system in combination a plurality of electrically-insulated track-sections, an electric circuit in one section adapted to be closed by the wheels and axles of a train in that section, an electromagnet in said circuit, a second electric circuit in the next adjacent section adapted to be closed by the wheels and axles of a train in that section, an electromagnet in said circuit, a third electric circuit, armatures in said circuit adapted to be operated by the magnets in the first two circuits, contacting buttons coacting with said armatures whereby when said electromagnets are energized the third circuit will be completed, an electromagnet in said third circuit, an armature adapted to be lifted by said magnet whereby a rail is electrically disconnected from the remainder of the section, an auxiliary circuit between two insulated parts of the moving train completed through the tracks between them and means whereby the breaking of said circuit operates the air-brakes as and for the purpose specified.

7. In a block-signaling system in combination a plurality of electrically-insulated track-sections, an open electric circuit in one section adapted to be closed by the wheels and axles of a train in that section, and means whereby the train will be stopped if said circuit fails to be operated as and for the purpose specified.

8. In a device of the class described in combination a plurality of electrically-insulated track-sections an electric circuit completed through the wheels and axles of a train in one section, an electromagnet in said circuit, an insulated rail at the end of said section, an armature situated below said magnet and adapted to be lifted thereby, whereby said insulated rail will be electrically disconnected from the remainder of the track as and for the purpose specified.

9. In a block-signaling system in combination a central insulated track-section, two electric circuits, adapted to be closed by the wheels and axles of trains in the adjacent outside sections, a third electric circuit, means whereby the closing of the aforesaid outside circuits completes the third circuit and means whereby the closing of the third circuit places train-stopping means at each end of said central section as and for the purpose specified.

10. In a block-signaling system in combination a central insulated track-section, two electric circuits adapted to be closed by the wheels and axles of trains in the adjacent outside sections, a third electrical circuit, means

whereby the closing of the aforesaid outside sections closes the third circuit, means whereby the closing of the third circuit electrically disconnects the rails at each end of said central section, an auxiliary electric circuit between two insulated parts of the moving train completed through the tracks between them and means whereby the breaking of said circuit operates the air-brakes as and for the purpose specified.

11. In a block-signaling system in combination a central track-section, two electric circuits adapted to be closed by the wheels and axles of the trains in adjacent outside sections, a third electrical circuit, means whereby the closing of the aforesaid outside circuits closes the third circuit, and means whereby the failure of the two outside circuits to operate places train-stopping means at the end of each section as and for the purpose specified.

12. In a block-signaling system in combination a central insulated track-section, two electric circuits adapted to be closed by the wheels and axles of trains in the adjacent outside sections, electromagnets in said circuit, armatures adapted to coact with said electromagnets, a third electric circuit adapted to be completed by the action of said electromagnets on said armatures when energized, electromagnets in said third circuit placed at each

end of said central track-section, armatures coacting with said electromagnets and adapted when operated to complete fourth electric circuits at each end of the said section, electromagnets in said fourth circuits and means whereby the operation of said electromagnets closes fifth electric circuits at each end of the track-section, electromagnets provided in said fifth circuits, armatures coacting therewith whereby an insulated rail is provided at the end of each section when said armatures are raised as and for the purpose specified.

13. In a block-signaling system in combination a central insulated track-section, two electric circuits adapted to be closed by the wheels and axles of trains in adjacent outside sections, a third electric circuit, means whereby the closure of aforesaid outside sections closes the third electric circuit, fourth electrical circuits situated at each end of said central section and adapted to be closed by the operation of said third circuit, and means in said fourth circuits for electrically insulating rails at each end of said central section as and for the purpose specified.

Signed at Toronto, in the Province of Ontario, this 1st day of May, 1905.

CLAUD DANIEL MCPHEE.
